SPOON AND METHOD OF MAKING THE SAME

Samuel Jennings, Jr., Masury, Ohio, assignor to
The Isaly Dairy Company, Youngstown, Ohio,
a corporation of Ohio

Application August 27, 1934, Serial No. 741,661

4 Claims. (Cl. 76—105)

This invention relates to spoons and especially to dipping spoons or scoops for transferring ice cream from a container to an ice cream cone. One object of the invention is to produce a spoon which will be strong and easily manipulated to take up the quantity of ice cream required to fill a cone and load the cream into the cone. Another object of the invention is to so improve the manufacturing process that the spoons may be rapidly finished and will be of all seams so that moisture cannot enter the handle and separation of the constituent elements cannot occur. These stated objects and other objects which will appear as the description proceeds are attained in the structure and process illustrated in the accompanying drawing, and the invention resides in certain novel features defined in the appended claims.

In the drawing:

Figure 1 is a side elevation of the completed spoon.

Figure 2 is a plan view, partly broken away and in section.

Figure 3 is a section on the line 3—3 of Figure 1.
Figure 4 is a bottom plan view.
25 Figure 5 is an enlarged section on the line 5—5
of Figure 4.

Figure 6 is a bottom plan view of the spoon before the stem has been sealed and the handle applied.

30 Figure 7 is a plan view of the blank.
In manufacturing a spoon according to the
present invention, there is provided a blank of
rustless sheet metal of suitable gage having a cor-
35 date major portion 1 and a tongue 2 extending
from the base of said major portion, slits 3 being
formed in the edges of the tongue at its junction
with the major portion of the blank, and the edges
of the tongue being slightly diverged adjacent the
slits so that ears 4 are formed.

40 The blank is subjected to pressure in dies or stamping whereby the major cordate member has its sides bent upwardly and its intermediate portion given an arcuate dished shape whereby to form the bowl 5 having a sharp pointed end 6 and relatively high sides 7, the edges of the sides slanting and diverging toward the two ends. The 45 butt end 8 of the bowl is broader than the entering end 6, and the ears 4 of the tongue are folded under and against the butt end to unite therewith in a graceful curve, as shown at 9. The tongue 2 is rolled by successive stages into a tubular stem 10, and prior to the last stage of the stem-forming process, a rod 11 of circular cross-section is disposed within the partly formed stem with one 50 end projecting longitudinally therefrom, and is

Cl. 76—105) spot-welded at the outer end of the stem. The folding or rolling is then completed, the result being the production of a tubular stem of circular cross-section fitting closely around the rod, as shown in Figure 5, with the ears 4 bearing against the under side of the bowl and the side edges of the tongue parallel and defining a slot 12 extending longitudinally of the stem. The slot 12 is closed and its sides, together with the edges of the ears 4, are permanently united with the rod and 10 the bowl, respectively, by electric welding, the weld 13 being finished so as to present a smooth surface merging into the surface of the bowl. A handle 14, preferably of hard rubber, is then forced over the end of the rod, the proportions of 15 the parts being such that the rod will bind in the bore of the handle and will be firmly held therein by friction while the end of the stem will enter the handle and will be sealed thereby effectually preventing the entrance of moisture. 20

20
By following the described method spoons may be rapidly produced at a low cost, and the finished spoon will be well adapted to dipping ice cream and transferring it to an ice cream cone. The tubular stem is strongly reenforced by the rod it 25 encloses so that bending or breaking of the stem is not apt to occur even when the spoon is forced into the hardest ice cream. It is to be particularly noted that the stem or shank is on a plane with or below the bottom of the bowl and, therefore, will not hinder any efforts to bring the butt end of the bowl into close relation to the cone which is to be filled, while the relatively high sides of the bowl will retain the ice cream until it is pushed or scraped off into the cone. 30
35

Having described my invention, what I claim is:

1. The method of manufacturing a spoon which consists in forming a blank having a major coordinate portion and a tongue projecting therefrom and shaping the blank longitudinally whereby to produce a bowl having a pointed end and relatively high sides and a tubular stem having ears bearing against the under side of the bowl at the butt end of the same, housing a rod in the stem, and welding the stem to the rod, and the ears to the bowl.

2. The method of manufacturing a spoon which consists in forming a blank having a major coordinate portion and a tongue projecting therefrom and shaping the blank longitudinally whereby to produce a bowl having a pointed end and relatively high sides, and a tubular stem having ears bearing against the under side of the bowl at the butt end of the same, housing a rod in the stem, and welding the stem to the rod, and the ears to 50 55

the bowl and then forcing a handle over the end of the rod and the stem.

3. A spoon comprising a pointed bowl having relatively high sides, a longitudinally slit tubular stem projecting therefrom, ears at the inner end of the stem bearing against the underside of the bowl, a relatively great distance forwardly beyond the juncture of the stem therewith, a weld closing the slit of the stem and permanently uniting the ears with the bowl, a rod mounted in the stem and fixed therein by the weld, said rod extending rearwardly beyond the stem, and a handle

having the extending end of the rod and the rear end of the stem embedded and fixed therein.

4. A spoon comprising a bowl having a pointed free end and relatively high sides having their peaks disposed rearwardly of the transverse center of the bowl and diverging toward the ends thereof, a stem formed on and projecting from the bowl and extending in a plane below the longitudinal center of the bowl, a rod secured in the stem and extending therefrom, and a handle secured to the rod and stem. 5
